[57] CLAIM

The ornamental design for a baby food jar holder, as shown and described.

DESCRIPTION

FIG. 1 is an isometric perspective view from the front, top and right side of a baby food jar holder, showing my new design;

FIG. 2 is a right side elevational view thereof; the left side, not shown, is a mirror image of the right side;

FIG. 3 is a rear elevational view;

FIG. 4 is a top plan view thereof; and,

FIG. 5 is a bottom plan view thereof.

FIG. 1

FIG. 2

FIG. 3

FIG. 4

FIG. 5
